Merle D. Gilgore

UNITED STATES PATENT OFFICE.

MORRIS B. MOSER, OF WELLS, MINNESOTA.

HYDROCARBON BURNER.

Application filed December 11, 1922. Serial No. 606,092.

To all whom it may concern:

Be it known that I, MORRIS B. MOSER, a citizen of the United States, residing at Wells, in the county of Faribault and State 5 of Minnesota, have invented certain new and useful Improvements in Hydrocarbon Burners; and I do hereby declare the following to be a full, clear, and exact description of the invention, such as will enable 10 others skilled in the art to which it appertains to make and use the same.

My invention provides a simple and highly efficient hydro-carbon burner which is adapted to burn not only the intermediate 15 grades such as kerosene and distillate, but also much lower grades of oil such as crude oil or even worn out lubricating oils.

Generally stated, the invention consists 20 of the novel devices and combinations of devices hereinafter described and defined in the claims.

The improved burner hereinafter described may, of course, be made in various 25 different sizes and it is adapted for application in furnaces, boilers, heating stoves, cooking stoves and the like. When applied in large fire pots such as that of furnaces and boilers, a plurality or group of individual burners will preferably be applied in 30 order that a very large range of variation in heating capacity may be taken care of by making the individual burners of different sizes.

In the accompanying drawings, which 35 illustrate the invention, like characters indicate like parts throughout the several views.

Referring to the drawings:

Fig. 1 is a plan view showing the improved burner;

Fig. 2 is a vertical section taken on the line 2—2 of Fig. 1;

Fig. 3 is a side elevation of the burner, the lower portion thereof being broken away;

Fig. 4 is a plan view of the burner with the deflecting cap of the burner removed; and

Fig. 5 is a plan view of the burner with both the deflecting cap and the stack cap removed, and with some parts sectioned.

The burner comprises a central air intake stack 6 preferably made up of sections telescopically connected at 7. The lower stack section 6 is shown as formed integral with a surrounding annular priming pan 8 from the bottom of which a drain pipe 9 is ex-

tended to a suitable point of discharge. The upper stack section 6 is shown as provided with an upwardly and outwardly flaring conical deflecting flange 10.

The fuel supply pipe 11 extends to a suitable source of supply such as a tank or a tank under air pressure and is passed axially upward through the air stack 6 and is centered and held in position by spider 65 brackets 12 and 13, provided respectively at the bottom and top of the stack. In this arrangement the air passes upward through the stack, but to facilitate lateral discharge at the upper end of the stack, auxiliary air 70 discharge ports 14 are provided in said stack.

The numeral 15 indicates a stack cap of inverted cup-shape form, the depending flange of which is circumferentially spaced 75 around and from the upper end of the stack. The fuel pipe 11 is passed through a central axial passage in the cap 15, and the said cap is held in operative position shown in the drawings by bearing lugs 16 on the extreme 80 upper end of the stack.

Located above and extending around the stack cap 15 is a deflecting cap 17 provided at its center with a raised hub 18 into which the delivery end of the fuel pipe 11 is extended with clearance. Preferably, the upper end of the fuel pipe 11 is threaded not for the purpose of engagement with the deflecting cap but to afford a plurality of fine 85 ribs around the delivery end of the fuel 90 pipe which will retard the downward flow of the oil.

The depending peripheral flange of the deflecting cap 17 for different purposes will be differently designed, but in the preferred 95 arrangement it is provided with a relatively shallow depending flange 19 that extends through approximately 180° and with which deeper depending flange 20 that extends through the other 180° of the circumference of said cap. The flange 19 is terminated above the lower edge of the flange of the stack cap 15 while the lower edge of the flange 20 extends nearly or quite into contact with the deflecting flange 10 of the 100 stack. The hub 18 of the deflecting cap is shown as provided with a knob or handle 21 which permits the deflecting cap to be readily given rotary adjustments around the axis of the stack and fuel pipe 11. The 105 stack cap 15 is provided with a shallow 110 standing annular flange 22 upon which the

deflecting cap loosely rests, and to facilitate the radial discharge of oil or fuel vapor, the said flange is provided with notches 23.

Operation.

When the burner is started into action for the first time, a priming charge of gasoline should be placed in the priming pan 8 and ignited so as to heat the metallic parts of the burner to quite a high temperature and then a supply of oil or hydro-carbon fluid should be turned on through the pipe 11. The fuel supply by the feed pipe 11 will slowly overflow its upper end and will run down the pipe into the stack cap 15, and the latter being hot will convert the oil into vapor. The air will be drawn up through the stack and deflected downward by the stack cap 15 and will be commingled with the fuel vapor at the exterior of said cap so that the flame produced will burn only outward of the flange of the cap 15. When the burner has been in operation a short time the space between the two caps 15 and 17 will be filled up with carbon, but this carbon will be of a porous or spongy character capable of absorbing and holding a considerable amount of oil or hydro-carbon fluid. This filling in of the said space with the carbon product is just what is desired for it is then utilized as a sort of wick, and thereafter in starting the burner, priming is not necessary, but it is only necessary to turn on the fuel supply and to ignite the oil at the exposed surface of the carbon deposit. When thus first starting the burner into action, the fuel will burn as oil, but the heat of combustion will soon make the metallic parts of the burner and the carbon deposit hot so that the fuel will be delivered to the air in the form of vapor. When the burner is in action after the carbon deposit has been formed there will be a very even distribution of the fuel vapor at the exposed surface of the carbon deposit. The air will be drawn from the burner radially outward and upward. With the deep semi-circular flange 20, the flame projected from the burner will be semi-circular and will project on that side that is away from the deep flange 20. By increasing or decreasing the circumferential extent of flange 20 the circumferential extent of the flame may be increased or decreased in reverse order and, of course, if the entire depending flange of cap 17 be of a consistent depth such as that of the flange 19, then there will be produced a circular or annular radially and up-

wardly projected flame. The edge of the deep segmental flange 20 may project where it will produce the greatest heating effect within the fire combustion within which it is applied. For instance, the cap may be adjusted so that all of the flame will be projected toward or against an adjacent wall of the fire pot or heater. This is especially important where individual burners are arranged in groups within the same fire pot or combustion chamber.

When the carbon deposit has been formed it will be self-maintaining, that is: surplus carbon at the exterior will be burned away and the interior deposit will be maintained up to a point where the space intervening between the two caps will be filled with the porous or sponge-like carbon deposit.

It will, of course, be understood that such a carbon deposit will absorb and hold very considerable amount of oil or fuel, and that as further oil supply is cut off from the fuel pipe 11 there will be a flame continued for a considerable time but gradually diminishing in intensity to a point where it goes out, and in lighting the burner there will be a flame gradually increasing in intensity up to a point of maximum intensity. Of course, the customary pilot light may be provided if desired, and hence the burner, even when intermittently operated, will give much more nearly the effect of a flame progressively varied in intensity to the heat requirement, than is the burner that goes completely on and completely off with the substantially instantaneous action. The statements above made are based on a long and continued actual use of the burner described.

What I claim is:

1. A hydro-carbon burner comprising an air intake stack, a stack cap spaced above and surrounding the upper end of said stack, of a deflecting cap located above said stack cap, and a fuel feed pipe extended upward through said stack and stack cap and delivering into the deflecting cap, said stack below said cap having an outstanding deflecting flange and said deflecting cap having a depending flange which, throughout a portion of a circle, terminates high above the deflecting flange of said stack and which throughout the remaining portion of the circle extends downward substantially to said deflecting flange.

2. The structure defined in claim 1 in which the deflecting cap is rotatably adjustable.

In testimony whereof I affix my signature.
MORRIS B. MOSER.
